DENTAL PLIERS

John Fuest, Glendale, N. Y.

Application July 10, 1957, Serial No. 670,906

6 Claims. (Cl. 32—62)

This invention relates to dental forceps.

It is an object of the present invention to provide dental forceps equipped with an air pressure mechanism for the purpose of moving a hammer-like detent in the gripping forceps whereby when the air pressure valve is actuated by the dentist the detent will be forced downwardly against the tension of springs, and upon release of the valve the springs will knock the detent upwardly against the tooth which is to be extracted.

Other objects of the present invention are to provide a dental forceps bearing the above object in mind which is of simple construction, is inexpensive to manufacture, has a minimum number of parts, is easy to use and efficient in operation.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a dental forceps embodying the features of the present invention.

Fig. 2 is a longitudinal sectional view taken along the line 2—2 of Fig. 1.

Fig. 3 is a fragmentary vertical sectional view taken along the line 3—3 of Fig. 2.

Fig. 4 is a fragmentary view similar to Fig. 2, but showing the valve in an open position.

Fig. 5 is a vertical sectional view taken along the line 5—5 of Fig. 2.

Fig. 6 is a vertical sectional view taken along the line 6—6 of Fig. 5.

Fig. 7 is a view similar to Fig. 5 but showing the position of the hammer-like detent when the valve is opened.

Fig. 8 is a vertical sectional view taken along the line 8—8 of Fig. 7.

Referring now more in detail to the drawings, there is shown a dental forceps, referred to collectively as 10, and including a pair of handle portions 11 and 12, substantially as illustrated.

The handle portion 12 is integrally formed with a jaw 13 while the handle portion 11 is integrally formed with a jaw 14, the ends of the jaws 13 and 14 being provided along their upper edges with extensions 15 and 16, respectively. The handle portion 12 adjacent the jaw 13 is provided with a flattened, circular portion 17, having a circular bore 18 (Fig. 2), the handle portion 12 being provided with a cutout 19 below the flattened portion 17, to pivotally receive a correspondingly flattened, circular portion 20 provided in the handle portion 11. The handle portion 11 is also provided with a cutout 21 which receives the flattened portion 17, the flattened portion 20 being provided with a bore aligned with the bore 18 of the flattened portion 17.

The flattened portion 17 and 20 of the handle portions 11 and 12, respectively, are pivotally connected to each other by means of a cylindrical member 22 having an

2

integrally formed circular flange 23 at one end and having internally threaded bore 24 at the other end (Fig. 3). A circular flange 25 is integrally formed with an externally threaded portion 26 adapted to be screwed into the internally threaded opening 24 whereby to pivotally connect the handle portions 11 and 12 together, as will be obvious.

The cylindrical member 22 is also integrally formed with a rearwardly extending portion 27 which terminates in a transverse hollow cylindrical portion 28, the side of cylindrical portion 28 remote from the portion 27 being integrally formed with an extension 29 having an externally threaded end 30. An air pressure line 31 is connected to the externally threaded end of the extension 29 by means of an internally threaded adaptor 32, the other end of the air line 31 being connected to a cylinder of compressed air, not shown. The outer surface of the adaptor 32 is knurled to facilitate connection of the air line 31 to the extension 29.

20 A piston valve 33 is slideable within the hollow cylinder 28 and is integrally formed with a piston rod or handle 34 extending outwardly through an opening at one end of the cylinder 28 and terminating in a button 35, the piston 33 being normally urged into the position of Fig. 2 by means of a compression spring 36. The piston 33 may be pushed to the position of Fig. 4 against the action of spring 36, by means of the thumb or other finger 37 (Fig. 4). The handle 12, it will be noted, is provided with an opening 38 which receives the handle 34 there-through.

25 The extension 29 is provided with an internal bore 39 connecting the air line 31 with the interior of the hollow cylinder 28, the piston 33 having a bore 40 adapted to be aligned with the bore 39 (Fig. 4). The piston 33 is also provided with an L-shaped bore 41 which communicates with an outlet opening 42 provided in the portion of cylinder 28 containing spring 36.

30 The cylindrical member 22 is provided with an internal bore 43 which communicates with the interior of hollow cylindrical member 28 by means of a longitudinal bore 44 provided in the extension 27 (Fig. 3), the rear end of the bore 44 being adapted to be aligned with the bore 40 (Fig. 4) when the valve is pushed or opened and adapted to be aligned with the bore 41 when the valve is closed (Fig. 2). Thus, upon pressing of the button 35, compressed air will be delivered to the bore 43 of cylindrical member 22.

35 The inner faces of the ends of jaws 13 and 14 are provided with cutout portions 45 and 46, respectively, the jaws 13 and 14 also being provided with bores 47 and 48, respectively, which open onto the cutouts 45 and 46 at one end and open onto bore 43 of the cylindrical member 22, at the other ends, the cylindrical member 22 having a bore 49 communicating with bore 47 and a bore 50 communicating with bore 48 (Fig. 3). The ends of bores 47 and 48, it will be noted, are enlarged adjacent the cylindrical member 22 to permit the angular displacement of the jaws 13 and 14 relative to each other necessary to grip the tooth while still permitting the bores 47 and 48 to be in contact with the bores 49 and 50, as will be obvious. Thus, upon pressing the button 35, compressed air will be delivered to the cutouts 45 and 46.

40 A pair of hollow rectangular housings 51 and 52 are positioned within the cutouts 45 and 46, the housing 51 being secured in position by means of a flange 53 and screws 54, while the housing 52 is secured in position by means of a flange 55 and screws 56. The bottom walls of the housing 51 and 52 are also secured within the cutouts 45 and 46. The housings 51 and 52 are, when positioned against the cutouts 45 and 46, entirely closed and communicate with the bores 47 and 48 by means of openings 59 and 60, respectively.

A cup-shaped member 61 is positioned within the housing 51 and is adapted for vertical movement therewithin, while a second cup-shaped member 62 is similarly positioned within the housing 52, the top wall of the housings 51 and 52 providing a stop for each of these cup-shaped members when the latter are in the raised positions of Fig. 6. The undersurface of each of the cup-shaped members 61 and 62 is integrally formed with a pair of longitudinally spaced hubs 63 which have secured therewithin a pair of vertical shafts 64, the lower ends of the shafts 64 passing downwardly through a pair of longitudinally spaced openings 65 provided in the bottom walls of each of the housings 51 and 52. Compression springs 66 sleeve each of the shafts 64 intermediate the hubs 63 and the bottom walls of the housings 51 and 52, these springs serving to normally retain the cup-shaped members 61 and 62 in the raised positions of Fig. 6. Gripper members or plates 67 are suitably secured to the lower ends of the shafts 64, as shown in Fig. 6, the gripper members 67 having grooved outer edges 68 adapted to cooperate with each other to engage the base of a tooth 69 when the handle portions 11 and 12 are squeezed together.

The central bottom portion of each of the cup-shaped members 61 and 62 is also integrally formed with a downwardly extending portion 70 which extends toward the openings 59 and 60 in an extension 71 and which terminates in an enlargement 72 adapted to overlie the openings 59 and 60, as shown in Fig. 6. The downwardly extending portion 70, the extension 71 and the terminal 72 are hollow, permitting compressed air from the openings 59 and 60 to be conducted into the cup-shaped members 61 and 62. It will be noted that by means of the enlarged terminals 72, the compressed air will be conducted into the cup-shaped members 61 and 62 when the latter are both in the upper and lower positions (see Figs. 6 and 8).

In operation, the push button 35 will be pressed inwardly to open the valve and to permit the compressed air to flow from air line 31 into the housings 61 and 62 and thence through the portions 72, 71 and 70 upwardly into the cup-shaped members 61 and 62, forcing the latter downwardly in piston-like action against the action of springs 66. This will lower the gripper members 67 to the position of Figs. 7 and 8, whereupon they are brought into tensional engagement with the base of the tooth 69 by squeezing handles 11 and 12. Upon release of the button 35, the spring 36 will disconnect the air line 31 and will permit the compressed air within the cup-shaped members 61 and 62 to escape rearwardly through the L-shaped bore 31 of the piston 33 and then outwardly of cylinder 28 through opening 42, thus permitting the springs 66 to snap the cup-shaped members 61 and 62 upwardly and thereby snapping the gripper members 67 upwardly to extract tooth 69. It will be noted that the top walls of the housings 61 and 62 serve as stops for the cup-shaped members 61 and 62.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A dental forceps comprising a pair of handles pivoted together, each of said handles having connected thereto a jaw, the outer ends of each of said jaws being hollow, a piston-like member slidable within each of said hollow ends, spring means for normally retaining said piston-like members in a raised position, external tooth gripping members at the bottom of each of said jaws and connected to said piston-like members, and means for supplying compressed air to each of said hollow jaw ends

whereby to move said piston-like members downwardly against the action of said spring means.

2. A dental forceps comprising a pair of handles pivoted together, each of said handles having connected thereto a jaw, the outer ends of each of said jaws being hollow, a piston-like member slidable within each of said hollow ends, spring means for normally retaining said piston-like members in a raised position, external tooth gripping members at the bottom of each of said jaws and connected to said piston-like members, and means for supplying compressed air to each of said hollow jaw ends whereby to move said piston-like members downwardly against the action of said spring means, said last-mentioned means comprising a hollow cylindrical member forming a bearing for pivotally connecting said handles together, a hollow extension extending rearwardly from said cylindrical member and communicating with the interior thereof, a hollow transverse cylindrical member at the end of said hollow extension, means for connecting the side of said transverse cylindrical member remote from said extension to a compressed air line, a piston within said hollow transverse shaft, said piston having a first bore adapted to connect said extension with the air line, said piston having a second substantially L-shaped bore adapted to connect said extension with the interior of said transverse cylinder, said transverse cylinder having an opening, spring means for urging said first bore of said piston out of alignment with said extension, a laterally extending rod connected to said piston, and an enlarged button on the end of said rod, said rod passing through an opening provided in one of said handles, said jaws having longitudinally extending bores, said first cylindrical member having a pair of openings connecting the interior thereof with said jaw bores.

3. A dental forceps comprising a pair of substantially S-shaped members, each of said members having a jaw portion and a handle portion connected by a flattened portion, means for pivotally connecting said flattened portions, each of said jaws at the ends thereof on adjacent faces having cutout portions, a pair of closed rectangular housings secured within said cutout portions, a pair of substantially cup-shaped members within each of said housings, said cup-shaped members being open on the top and adapted for sliding movement within said housings, downwardly extending members connected to the bottom of each of said cup-shaped members extending downwardly and slidably through the bottoms of said housings, a pair of tooth gripper members connected to the bottoms of said downwardly extending members, said gripper members being adapted when brought together to engage the base of a tooth, spring means surrounding said downwardly extending members and adapted to retain said cup-shaped members in an upper position with said gripping members retracted, and means for supplying compressed air to said cup-shaped members whereby to urge the same downwardly against the action of said spring means.

4. A dental forceps comprising a pair of substantially S-shaped members, each of said members having a jaw portion and a handle portion connected by a flattened portion, means for pivotally connecting said flattened portions, each of said jaws at the ends thereof on adjacent faces having cutout portions, a pair of closed rectangular housings secured within said cutout portions, a pair substantially cup-shaped members within each of said housings, said cup-shaped members being open on the top and adapted for sliding movement within said housings, downwardly extending members connected to the bottom of each of said cup-shaped members extending downwardly and slidably through the bottoms of said housings, a pair of tooth gripper members connected to the bottoms of said downwardly extending members, said gripper members being adapted when brought together to engage the base of a tooth, spring means surrounding said downwardly extending members and adapted to re-

tain said cup-shaped members in an upper position with said gripping members retracted, means for supplying compressed air to said cup-shaped members whereby to urge the same downwardly against the action of said spring means, said last-mentioned means comprising said flattened portions having aligned bores, a cylindrical member within said aligned bores, said cylindrical member having a hollow bore, each of said jaws having a longitudinal bore extending from said housings to said cylindrical member, said cylindrical member having secondary bores communicating with said longitudinal jaw bores, each of said housings having an opening communicating with said longitudinal bores, a depending, hollow communicating at one end with the interior of said cup-shaped members and at the other end with said openings provided in said housings, and means for supplying compressed air to the interior bore of said cylindrical member.

5. A dental forceps comprising a pair of substantially S-shaped members, each of said members having a jaw portion and a handle portion connected by a flattened portion, means for pivotally connecting said flattened portions, each of said jaws at the ends thereof on adjacent faces having cutout portions, a pair of closed rectangular housings secured within said cutout portions, a pair of substantially cup-shaped members within each of said housings, said cup-shaped members being open on the top and adapted for sliding movement within said housings, downwardly extending members connected to the bottom of each of said cup-shaped members extending downwardly and slidably through the bottoms of said housings, a pair of tooth gripper members connected to the bottoms of said downwardly extending members, said gripper members being adapted when brought together to engage the base of a tooth, spring means surrounding said downwardly extending members and adapted to retain said cup-shaped members in an upper position with said gripping members retracted, means for supplying compressed air to said cup-shaped members whereby to urge the same downwardly against the action of said spring means, said last-mentioned means comprising said flattened portions having aligned bores, a cylindrical member within said aligned bores, said cylindrical member having a hollow bore, each of said jaws having a longitudinal bore extending from said housings to said cylindrical member, said cylindrical member having secondary bores communicating with said longitudinal jaw bores, each of said housings having an opening communicating with said longitudinal bores, a depending, hollow member communicating at one end with the interior of said cup-shaped members and at the other end with said openings provided in said housings, means for supplying compressed air to the interior bore of said cylindrical member, said last-mentioned means comprising a hollow rearwardly extending portion connected to said first cylindrical member, a transverse hollow cylindrical member at the end of said rearwardly extending member, a piston valve within said transverse cylindrical member, a hollow extension on said transverse cylindrical member, means for supplying compressed air to said extension, said valve having a first bore adapted to connect said extension with said rearwardly extending portion, a spring intermediate said valve and one end of said transverse cylindrical member, said cylinder surrounding said spring having an outlet opening, said valve having a second substantially L-shaped bore adapted to connect said extension to an air line comprising said extension being externally threaded and adapted to receive thereon an internally threaded adaptor connected to the air line, said means for moving said piston against the action of said spring comprising a piston rod extending outwardly and terminating in an enlarged button, one of said handle portions having an opening receiving said piston rod therethrough.

6. A dental forceps comprising a pair of substantially S-shaped members, each of said members having a jaw portion and a handle portion connected by a flattened portion, means for pivotally connecting said flattened portions, each of said jaws at the ends thereof on adjacent faces having cutout portions, a pair of closed rectangular housings secured within said cutout portions, a pair of substantially cup-shaped members within each of said housings, said cup-shaped members being open on the top and adapted for sliding movement within said housings, downwardly extending members connected to the bottom of each of said cup-shaped members extending downwardly and slidably through the bottoms of said housings, a pair of tooth gripper members connected to the bottoms of said downwardly extending members, said gripper members being adapted when brought together to engage the base of a tooth, spring means surrounding said downwardly extending members and adapted to retain said cup-shaped members in an upper position with said gripping members retracted, means for supplying compressed air to said cup-shaped members whereby to urge the same downwardly against the action of said spring means, said last-mentioned means comprising said flattened portions having aligned bores, a cylindrical member within said aligned bores, said cylindrical member having a hollow bore, each of said jaws having a longitudinal bore extending from said housings to said cylindrical member, said cylindrical member having secondary bores communicating with said longitudinal jaw bores, each of said housings having an opening communicating with said longitudinal bores, a depending, hollow member communicating at one end with the interior of said cup-shaped members and at the other end with said openings provided in said housings, means for supplying compressed air to the interior bore of said cylindrical member, said last-mentioned means comprising a hollow rearwardly extending portion connected to said first cylindrical member, a transverse hollow cylindrical member at the end of said rearwardly extending member, a piston valve within said transverse cylindrical member, a hollow extension on said transverse cylindrical member, means for supplying compressed air to said extension, said valve having a first bore adapted to connect said extension with said rearwardly extending portion, a spring intermediate said valve and one end of said transverse cylindrical member, said cylinder surrounding said spring having an outlet opening, said valve having a second substantially L-shaped bore adapted to connect said extension to an air line comprising said extension being externally threaded and adapted to receive thereon an internally threaded adaptor connected to the air line, said means for moving said piston against the action of said spring comprising a piston rod extending outwardly and terminating in an enlarged button, one of said handle portions having an opening receiving said piston rod therethrough.
